UNITED STATES PATENT OFFICE.

ANTHONY CONTI, OF BROOKLYN, NEW YORK.

LETTERING DEVICE.

Application filed February 7, 1927. Serial No. 166,571.

This invention relates to improvements in lettering devices and particularly to that kind of lettering device shown and described in my U. S. Letters Patent #1,611,140, dated

5 December 14th, 1926.

The primary object of the invention resides in a lettering device in which a series of characters are marked out upon a disk, and which characters may be brought into 10 registry with a suitable indicating mark, and a letter or numeral printed by moving a sharp pointed lettering pen or pencil about the walls of the cut-out character and which device is adjustably mounted upon a T-square for movement over the surface of the 15 paper to be printed upon.

Another object of the invention is to embody a lettering device upon a T-square so that the same is always maintained in a horizontal position to assure perfect alignment 20 of the characters as they are printed.

Another object of the invention is to provide a lettering device in which the circular disk or stencil may be locked after the selected characters to be printed have been 25 moved to the proper adjusted position, and a means whereby the characters to be printed may be accurately spaced from the last printed character.

30 A further object is to provide a lettering device for attachment to T-squares which is simple in construction, inexpensive of manufacture, and simple of operation.

With these and other objects in view, the 35 invention resides in certain novel construction and combination and arrangement of parts, the essential features of which are hereinafter fully described, are particularly pointed out in the appended claims, and are 40 illustrated in the accompanying drawing, in which:—

Figure 1 is a top plan view of my improved lettering device in position upon a T-square and drawing board.

45 Figure 2 is a front edge elevation of the same.

Figure 3 is an end elevation of the same.

Figure 4 is a vertical sectional view on the line 4—4 of Figure 1.

50 Figure 5 is a detail sectional view on the line 5—5 of Figure 1.

Referring to the drawings, the reference character A designates a drawing board and B a sheet of paper mounted thereon. A T-square 10 is slidable over the drawing board and has a head 11 engageable with one side

edge of the board and an adjustable head 12. Flat yieldable springs 13 are interposed between the head 12 and the opposite edge of the board. The head 12 is provided with a lip 14 which is slidably received in an elongated slot 15 provided in the T-square, whereby the T-square may be adjusted to drawing boards of different widths. The top face of the straight edge of the T-square may be provided with graduations in order that the same may act as a ruler in addition to a straight edge. A clamping nut 16 serves to hold the head 12 in an adjusted position and which is threaded on the free end of a stud which extends from the head 12, while a set screw 17 is carried by the head and may be screwed up tight against the side edge of the board for holding the T-square against sliding movement.

A carriage 18 is slidably mounted upon the T-square 10 and is held in frictional engagement therewith by flat springs 19 interposed between the bottom wall of the carriage and the under edge of the T-square. These springs prevent accidental sliding movement of the carriage with respect to the T-square but permit of the free manual sliding movement of the same. A gauge 20 is slidably mounted upon a track 21 provided on the carriage 18 and which is of a transparent material such as celluloid or the like to permit the drawing paper B to be visible therethrough for a purpose to be presently described.

The carriage 18 also supports a pair of spaced arms 22, one of which is graduated to provide a scale 23 and which scale serves as a ruler for measuring the distance between the horizontal rows of letters to be printed. A bridge or cross piece 24 connects the arms 22 but is offset with respect to the arms so as to dispose the disk 25 in the plane of the arms. The disk 25 is of a transparent material and is rotatably mounted upon a stud 26 which extends from the bridge and is retained thereon by a nut 27 threaded to the free end thereof. The outer free ends of the arms 22 are bent at right angle to provide legs 28 for spacing the circular disk 105 and arms from the surface of the paper to be printed upon. The circular disk 25 is transparent so as to be seen through and is divided up into a plurality of concentric fields, each of which is provided with characters 29 in the nature of letters or parts of letters of the alphabet and numerals, and

which are cut out therefrom so that the disk in reality is no more than a stencil. The outermost field contains the larger size characters but which gradually diminish in size 5 toward the axis of the disk. The disk 25 is supported above the paper by the bridge piece 24 and by a cross piece 30 which connects the arms 22 adjacent their point of contact with the straight edge of the T-square. The bridge piece 30 has its longitudinal edges recessed as at 31 to accommodate and support the peripheral edge of the disk at a point where the characters are printed. The bridge piece is graduated to provide a scale 32 with which the gauge 20 10 co-acts for measuring the distance between the last printed character and the next character to be printed.

The peripheral edge of the disk 25 is notched as at 33 on a radial line with the characters and which notches receive a lug 34 which is carried by a spring strip 35 mounted on one of the arms 22, and which strip is mounted in horizontal alignment 20 with the axis of the disk. The spring strip 35 tends to normally hold the lug out of engagement with the notches of the disk but is engageable therewith upon the manual depression of the same after the said disk has been adjusted to bring the selected character 25 into printing position. The operator holds the spring strip depressed until the character has been printed, after which it is released and automatically disengages the disk to allow free rotation of the same in bringing the next selected character into printing 30 position.

In operation, when it is desired to print any particular character, the selected character 40 being on a radial line 36, is brought into alignment with the vertical axis of the disk irrespective of the field in which the character may reside. Assume it is desired to print the word "C A T" in large size letters. The T-square is moved to a horizontal position so that the letters to be printed may be made on the desired plane. The disk is rotated to bring the letter C into vertical alignment with the axis of the disk and the disk is locked by the manual depression of the spring 35 by the left hand of the operator to cause the lug 34 to engage in the notch which is in register therewith. A sharp pointed pen or pencil may now be inserted 45 through the cut-out character C moved about the walls of the same to cause the outline of the character to be inscribed upon the paper. The next letter being A, the operator releases the spring lock 35 and rotates the disk to bring the character A in printing position, but before making an impression, the carriage 18 is shifted toward the right and the gauge 20 adjusted with respect to the printed letter C and the cut-out 50 letter A to accurately measure the space be-

tween the letters, it being understood that the printed letter C is visible through the disk and gauge as these parts are of transparent material. This measurement is made upon the scale 32 by moving the gauge 20 70 into alignment with the end of the printed letter C and then determining the distance between the letter C and the center of the letter A, which letter A is in alignment with one of the graduations on the scale 32. The same operation is performed in printing the letter as that previously described and after the printing of the letter A, the character T is brought into position and printed in the same manner. 75

The device may be removed from the T-square 10 when not in use by removing the nut 16 and disengagement of the head 12 which permits the carriage 18 to be slid off the end of the same. 80

While I have described what I deem to be the most desirable embodiment of my invention, it is obvious that many of the details may be varied without in any way departing from the spirit of my invention, and I therefore do not limit myself to the exact details of construction herein set forth nor to anything less than the whole of my invention limited only by the appended claims. 95

What is claimed as new is:—

1. In a lettering device, a carriage structure adapted to be slidably mounted upon said T-square, said carriage structure including a pair of spaced arms, a bridge piece connecting said arms, a disk having a series of punched characters provided thereon and rotatably mounted on said bridge piece, said disk having notches provided in its peripheral edge, and a depressible member carried by one of said arms and engageable with the respective notches to lock said disk against rotation with the selected character in printing position. 100

2. A lettering device comprising a pair 110 of spaced arms, a pair of bridge pieces connecting said arms, and a disk rotatably mounted on one of said bridge pieces and having its peripheral edge overlapping the other of said bridge pieces for supporting 115 said disk in spaced relation to the surface to be printed upon, said disk having a series of punched characters provided therein.

3. A lettering device comprising a frame embodying a pair of spaced arms and a pair 120 of bridge pieces connecting said arms, a disk rotatably mounted on one of said bridge pieces and having its peripheral edge overlapping the other of said bridge pieces for supporting said disk in spaced relation to 125 the surface to be printed upon, said disk having a series of punched characters provided therein, and a carriage supported by said frame and adapted to receive a T-square for slidably mounting the device thereon. 130

4. In a carriage structure adapted to be slidably mounted upon a T-square, said carriage structure including a pair of spaced arms, a bridge piece connecting said arms, and a disk having a series of punched characters provided thereon and rotatably mounted on said bridge piece.
5. In a lettering device, a carriage structure adapted to be slidably mounted upon a T-square, said carriage structure including a pair of spaced arms, a bridge piece connecting said arms, a disk having a series of punched characters provided thereon and rotatably mounted on said bridge piece, a gauge slidably mounted on said carriage structure for co-action with a scale provided
- thereon for accurately spacing the character to be printed with respect to the last printed character.
6. A lettering device comprising a carriage adapted to be slidably mounted upon a T-square, a frame structure supported by said carriage, a disk having a series of punched characters provided thereon and rotatably supported by said frame structure, a gauge slidably mounted on said carriage, there being a scale provided on said frame structure for co-action with said gauge. 20 25

In testimony whereof I have affixed my signature.

ANTHONY CONTI.
